UNITED STATES PATENT OFFICE.

HENRY G. RUNNE AND FRED T. RUNNE, OF ROCHESTER, NEW YORK.

DESIGN FOR A DIRECTION INDICATOR FOR MOTOR VEHICLES.

Application filed October 16, 1928. Serial No. 28,512. Term of patent 14 years.

To all whom it may concern:

Be it known that we, HENRY G. RUNNE and FRED T. RUNNE, citizens of the United States, residing at Rochester, in the county of Monroe and State of New York, have invented a new, original, and ornamental Design for a Direction Indicator for Motor Vehicles, of which the following is a specification, reference being had to the accompanying drawing, forming part thereof.

In the drawing:

Fig. 1 is a top view of a direction indicator for motor vehicles showing our design;

Fig. 2 is a side view showing our new design; and

Fig. 3 is another side view showing our new design.

We claim:

The ornamental design for a direction indicator for motor vehicles, as shown.

HENRY G. RUNNE.

FRED T. RUNNE.
